UNITED STATES PATENT OFFICE

NATHAN C. HUNT, OF SALEM, OHIO

ROLLING MILL COOLING DEVICE

Application filed November 26, 1929. Serial No. 409,834.

The invention relates to rolling mills, and more particularly to the control of roll temperatures by cooling the same.

In the operation of rolling mills for rolling sheets, strips, plates and various industrial shapes, from steel, aluminum, brass and the like, it is necessary to control the temperatures of the rolls and particularly the roll necks during the rolling operation so that 10 the resulting product will have certain desired predetermined characteristics.

In the past, the rolls have usually been cooled by externally applying a cooling medium to the rolls, and the roll necks as by spraying water or blowing cold air thereon. This method of roll cooling does not evenly cool the same and the material being rolled by the rolls consequently does not have uniform characteristics.

20 It has been found that rolls may be very evenly and uniformly cooled by introducing a cooling medium into the interior of the rolls, but difficulties have been encountered in providing a way for connecting a cooling medium supply line with each roll for introducing a cooling medium such as water, oil or air into the interior of the roll, because the roll is a rotating body and the means for introducing the cooling medium therein must 25 for all practical purposes be stationary.

Devices have been made in the past in an attempt to overcome these difficulties, but they have been unsuccessful because they have included a positive support for the device separate and apart from the connection of the device with the roll.

35 One of the objects of the present invention is therefore to provide for cooling rotating rolling mill rolls by introducing a cooling medium into the interior of the roll from a source of cooling medium supply.

40 A further object of the invention is to provide a self contained construction which may be connected with or disconnected from a roll as a unit, and which has no support excepting its connection with the roll.

45 A further object of the invention is to provide a construction on which any ordinary repairs may be quickly and easily made when 50 the rolls are idle, and a construction which

may be readily and quickly repaired in a very short space of time should a break-down occur during the operation of the rolls.

And finally, an object of the invention is to provide a construction which may be readily and easily installed in connection with present types of rolls, and a construction having a simple design, and a slight initial cost.

The above and other objects may be attained by providing a cooling device herein-after described in detail, which may be generally stated as including a hollow roll, a flanged coupling member secured in an end portion of the roll, a stationary casing having supply and discharge passages therein, and means for connecting the coupling member and the casing together, a combined injector and discharge tube being carried by the casing and extending into the hollow interior of the roll.

55 A preferred embodiment of the invention is shown in the accompanying drawings in which

60 Figure 1 is a side elevation of a rolling mill showing the improved cooling device applied thereto; and

65 Fig. 2 is an enlarged sectional view through the cooling device applied to a roll, taken substantially on the line 2-2, Fig. 1.

70 Similar numerals of reference indicate corresponding parts throughout the several figures of the drawings.

75 The housing of a conventional rolling mill is shown at 10, in which is journaled upper and lower rolls 11 and 12, each roll being provided at opposite ends with necks 13 which are mounted in customary brasses 14 and 14', and the rolls are provided with the usual wabblers 15 at their ends. The upper brass 14 is mounted in the movable head 16 which may be vertically adjusted in the housing 10 as by the usual screw 17.

80 Each roll 11 and 12 may be hollow by being provided with an axial internal bore 18 shown in Fig. 2, the one end of the bore not shown in the drawings is preferably plugged up, the other end thereof being counterbored at 19, threaded at 20 and countersunk at 21.

85 90 95 The cooling device generally indicated at

22 may be coupled with the roll 11 or 12 by connecting a flanged threaded tubular coupling member 23 within an end portion of the roll bore. The coupling member 23 may be provided with a conically tapered portion 24 for engaging the roll countersunk portion 21 when the threads 25 of the coupling member are engaged with the threads 20 of the roll. The inner end 26 of the coupling member 23 is received within the counterbore 19 of the roll and the interior tubular portion 27 of the coupling member 23 may be counterbored at 28 for receiving an "Arguto" wood bearing 29 for a purpose to be hereinafter set forth. The outer end of the coupling member 23 is preferably counterbored at 30 and provided with flanges 31 and 31a.

The cooling device 22 preferably includes a hollow casing 32, which has an enlarged cylindric portion 33 preferably threaded at 34. The coupling member 23 and the casing 32 are connected together in a manner permitting relative rotary movement by a sleeve 35 provided with an internal flange 36, and threaded at 37. The enlarged cylindric portion 33 may be counterbored at 38 to have a diameter equal to the diameter of the counterbore 30 in the coupling member 23.

In connecting the coupling member and casing together, a split ring flanged floating "Arguto" wood bearing 39 is interposed between the flanges 36, 31 and 31a, and another floating "Arguto" wood bearing 40 is interposed between the flange 31 and the enlarged cylindric portion 33. The threads 37 of the sleeve 35 are then screwed onto the threads 34 of the casing so as to draw the several parts tightly together, the sleeve is then backed off a fraction of a turn and the set screw 40a is tightened up to permanently secure the sleeve 35 to the casing 32.

The casing has a threaded passage 41 for engaging a cooling medium supply or inlet hose coupling adapted 42, and has a threaded passage 43 for engaging the cooling medium outlet hose coupling adapter 44. The adapter 42 is preferably axially aligned with the casing 32, and the internal bore 18 of the roll 11. A cooling medium injector tube or duct 45 is preferably connected by threads 46 with the interior of the casing 32 in axial alignment with the adapter 42 and the injector tube is locked in place by the jam nut 46a which abuts against the inner end 47 of an outlet tube or duct 48, the outer end of which is seated as at 49 against a counterbore 50 provided in the casing 32 adjacent the threads 46. For positively securing the parts together, a lock nut 46a' may be provided for the jam nut 46a. Substantially midway between its ends, the outlet tube 48 is journaled within the "Arguto" bearing 29 which provides a support for the tube, the outlet tube in turn supporting the injector tube 45 because of the jam nut connection therewith.

70 Openings 51 are formed adjacent the inner end 47 of the outlet tube for providing a communication between the interior of the roll bore 18 and the passageway 52 formed between the interior of the outlet tube 48 and exterior of the injector tube 45. Adjacent its outer end 49, the outlet tube 48 has openings 53 similarly formed therein, providing a communication between the passageway 52 and an annular channel 54 formed within the interior of the casing 32. The annular channel 54 communicates as at 55 with the outlet coupling adapter 44.

75 An expansible rubber sleeve 56 is inserted within the aligned counterbores 30 and 38 when the casing 32 and coupling 23 are being connected together, for sealing the joint therebetween. The rubber sleeve 56 is provided with a plurality of perforations 57 aligned with annular channels 57a for a purpose which will be hereinafter described.

80 The casing 32 is likewise provided with a plurality of ears 58 for a purpose which will also be hereinafter described.

85 Referring to Figure 1, hoses 59 and 60 may be coupled as at 42a to each inlet adapter 42 of each cooling device provided on each of the rolls 11 and 12 and these hoses may be connected at their other ends to a common source of cooling medium supply by piping 61. 90 Similarly, hoses 62 and 63 may be connected with the outlet adapter 44 of the respective cooling devices which hoses 62 and 63 communicate with a common discharge line by piping 64.

95 The cooling devices 22 may be connected together to prevent relative non-rotative movement by loosely passing a rod 65 through the aligned openings 66 in the ears 58 projecting from the respective cooling devices.

100 The operation of the device is as follows: A cooling medium, which is preferably cold water when the device disclosed in the drawings is utilized, is forced under pressure through the supply piping 61, the hose connections 59 and 60, through the adapters 42, and through each injector tube 45 in the direction shown by the arrows in Fig. 2. The water upon being dispelled from the inner end 45' of the injector tube, which inner end is preferably located adjacent the plugged end of the roll, passes backward through the bore 18 in the roll for absorbing heat from the roll. The flowing water then passes through the openings 51 in the outlet tube 48, along the passage 52, through the openings 53, along the annular channel 54, out the respective outlet adapters 44, through the outlet hose connections 62 and 63 to the discharge pipe 64.

105 110 115 120 125 130 A certain amount of water leaks between the "Arguto" bearing 29 and the outlet tube 48 for providing lubrication between the rubber sleeve 56. This water for lubrication reaches the surface to be lubricated through the openings 57. In order to assure that water

for lubrication will reach the rubber sleeve 56, openings 57b may be provided in the outlet tube 48.

The roll 11 and contained coupling member 23 is continuously rotating. The "Arguto" bearings 39 and 40 may rotate with the coupling member 23 or may remain stationary with respect to the casing 32 during rotation of the roll.

10 In any event during operation of the roll there are rubbing surfaces either between the bearing 40 and the enlarged cylindric portion 33, or between the bearing 40 and the flange 31; and between the bearing 39 and the flange 31, or between the bearing 39 and the flange 36.

The rubber sleeve 56 may remain stationary with respect to the casing 32, or may rotate with the roll. In any event there are rubbing surfaces either between the sleeve 56 and the counterbore 38 or between the sleeve 56 and the counterbore 30. Because of the water pressure against the interior of the rubber sleeve 56, the joint between the casing 32 and 20 the coupling member 23, where the bearing 40 is interposed, is sealed against water leakage.

The casings 32 are maintained stationary during rotation of the rolls by the rod 65 which passes loosely through the holes 66 in each ear 58. If it is at any time necessary to repair the cooling device, the couplings 42a and 44a may be disconnected from the coupling adapters 42 and 44, the set screw 40a 35 may be unloosened, and the sleeve 35 unscrewed, at which time the casing and permanently connected injector tube may be withdrawn as a unit from the roll and repaired; and if the roll is to be repaired, the coupling member 23 may be disconnected therefrom by applying a wrench to the flange 31a of the coupling member.

It is pointed out that the only support for the cooling device is the sleeve 35 which connects the casing 32 with the coupling member 23. Thus the device is free to wabble and weave with the roll but is prevented from rotating with the roll because of the rod 65.

I claim:

50 1. A device for cooling internally bored rolling mill rolls including, a casing provided with cooling medium inlet and outlet passages, a flanged tubular coupling member adapted for connection with the roll bore, means connecting the coupling flange and casing permitting relative rotary movement between the same, floating bearings between the coupling member flange, the casing and the connecting means, and cooling medium inlet and outlet ducts carried by the casing extending through the coupling and adapted for insertion within the roll bore.

2. A device for cooling internally bored rolling mill rolls including, a casing provided with cooling medium inlet and outlet pas-

sages, a flanged tubular coupling member adapted for connection with the roll bore, means connecting the coupling flange and casing permitting relative rotary movement between the same, floating bearings between the coupling member flange, the casing and the connecting means, means for sealing the connection between the coupling and the casing, and cooling medium inlet and outlet ducts carried by the casing extending through the coupling and adapted for insertion within the roll bore.

3. A device for cooling internally bored rolling mill rolls, including a casing provided with cooling medium inlet and outlet passages, a tubular coupling member adapted for connection with the roll bore, means connecting the coupling and casing permitting relative rotary movement between the same, means for sealing the connection between the coupling and casing, and cooling medium inlet and outlet ducts carried by the casing extending through the coupling and adapted for insertion within the roll bore.

4. A device for cooling internally bored rolling mill rolls, including a casing provided with cooling medium inlet and outlet passages, a tubular coupling member adapted for connection with the roll bore, means connecting the coupling and casing permitting relative rotary movement between the same, an expansive sleeve for sealing the connection between the coupling and casing, and cooling medium inlet and outlet ducts carried by the casing extending through the coupling and adapted for insertion within the roll bore.

5. A device for cooling internally bored rolling mill rolls including, a casing provided with cooling medium inlet and outlet passages, a tubular coupling member adapted for connection with the roll bore, means connecting the coupling and the casing permitting relative rotary movement between the same, a bearing carried by the coupling member, a cooling medium outlet tube communicating with the casing outlet passage carried by the casing journaled in the bearing and adapted for insertion within the roll bore, a cooling medium injector tube communicating with the casing inlet passage carried by the casing located within the outlet tube and adapted for insertion within the roll bore, and means connecting the outlet tube and injector tube together for forming a support for the injector tube within the roll bore.

6. A device for cooling internally bored rolling mill rolls including, a casing provided with cooling medium inlet and outlet passages, a tubular coupling member adapted for connection with the roll bore, means connecting the coupling and casing permitting relative rotary movement between the same, means for sealing the connection between the coupling and casing, a bearing carried by the coupling member, a cooling me-

dium outlet tube communicating with the casing outlet passage carried by the casing journaled in the bearing and adapted for insertion within the roll bore, a cooling medium 5 injector tube communicating with the casing inlet passage carried by the casing located within the outlet tube and adapted for insertion within the roll bore, and means connecting the outlet tube and injector tube together 10 for forming a support for the injector tube within the roll bore.

7. In combination with a rotatable rolling mill roll having an internal bore, a casing provided with cooling medium inlet and outlet 15 passages, means for maintaining the casing stationary when the roll is rotated, a coupling connected with the roll bore and rotatable with the roll, means supporting and journaling the casing on the coupling permitting relative rotary movement between the casing and coupling, and cooling medium inlet and outlet members stationarily mounted on the casing and journaled in the coupling forming communications between the 20 casing and roll bore.

8. In combination with a rotatable rolling mill roll having an internal bore, a casing provided with cooling medium inlet and outlet 25 passages, means for maintaining the casing stationary when the roll is rotated, a coupling connected with the roll bore and rotatable with the roll, means supporting and journaling the casing on the coupling permitting relative rotary movement between the 30 casing and coupling, means for sealing the connection between the casing and coupling, and cooling medium inlet and outlet members stationarily mounted on the casing and journaled in the coupling forming communications between the 35 casing and roll bore.

9. In combination with a plurality of rotatable rolling mill rolls having internal bores, a casing provided with cooling medium inlet and outlet passages for each roll, a coupling 45 connected with each roll bore, means supporting and journaling each casing on its respective coupling permitting relative rotary movement between respective casings and couplings, cooling medium inlet and outlet 50 communications between the respective casings and roll bores, and means connecting the casings together maintaining the same stationary when the rolls are rotated.

10. A device for cooling internally bored 55 rotatable rolling mill rolls including a casing provided with cooling medium inlet and outlet passages, means for maintaining the casing stationary, a rotatable tubular coupling member adapted for connection with the roll bore, means supporting and journaling the 60 casing on the coupling permitting relative rotary movement between the casing and coupling, and cooling medium inlet and outlet ducts stationarily mounted on the casing and journaled in and extending through the coup- 65

ling adapted for insertion within the roll bore.

In testimony that I claim the above, I have hereunto subscribed my name.
